ELECTROCATALYTIC GAS IGNITER

John Massier, Greensburg, Pa., assignor to Servel,
Inc., New York, N. Y., a corporation of Dela-
ware

Application May 31, 1950, Serial No. 165,273

8 Claims. (Cl. 317—83)

1

This invention relates to gas igniters and particularly to electro-catalytic igniters for domestic gas ranges.

This application is a continuation-in-part of and relates back for common subject matter to my copending application Serial No. 692,894, filed August 24, 1946, which is now abandoned.

With gas igniters and particularly with igniters for domestic gas ranges it is an absolute necessity that the igniter be quick and dependable in operation. Also, it is desirable that such an igniter have a long life and that it be free from maintenance requirements.

Electro-catalytic igniters have been used heretofore on gas ranges and have met with reasonable success. However, these igniters have generally been constructed of a single coil or loop of wire in such a manner that when any part of the coil or loop fails, as by excessive temperatures, the whole igniter fails and must be replaced in a relatively short period of time as compared with the life of the average gas range.

I have discovered an ideal igniter for use on domestic gas ranges, that is, an igniter that is quick, dependable, has a long life and is substantially free of maintenance requirements. Such an igniter is constructed of a plurality of strands of catalytically active material wherein the same voltage is imposed upon the several strands in parallel. Each of the wires or strands of a single igniter has a different current flow characteristic. This is accomplished by providing a plurality of strands of different dimensions. In a single igniter the several strands may be of uniform length but of varying cross-sectional area; the cross-sectional area may be uniform, and the lengths varied; or both the length and cross-sectional area may be varied, so long as the current flow characteristics of the several strands are different in a single igniter.

An extensive study of the temperature characteristics of the individual strands of the multi-strand electro-catalytic igniters composed of various numbers of strands of wire, of various diameters and lengths, and of various catalytically active materials, revealed that the wire temperatures increase as the number of ignitions increases. The rate of temperature rise is slow initially but greatly accelerates as higher temperatures are reached. Life tests on electro-catalytic igniters operating on a 15 second cycle (5 seconds on and 10 seconds off), during which time gas to a burner and electricity to an igniter were initiated simultaneously, were used as the basis of evaluating igniter durability and the time

2

lapse in seconds from this initiation until the burner was ignited was taken as the igniter speed.

Wire durability was found to be primarily a function of starting temperature. The lower the operating temperature of the heated wires of a new igniter the longer the life which could be expected. The minimum wire temperature which effected satisfactory ignition of methane, for example, was from 900 to 1000° C. It was found that the durability of electro-catalytic igniters operating in conjunction with a flash tube ignition system can be presented graphically when plotted on the basis of number of ignitions versus initial strand temperature. Curves drawn through such data are relatively smooth and indicate that decidedly longer lives are obtainable when starting temperatures under 1000° C. are employed. Such durability curves for different thicknesses of platinum wire strands are relatively close together whereas similar curves for different thicknesses of platinum-rhodium alloy (90 : 10) strands show a decided spread. The smaller diameter wires of platinum-rhodium (90 : 10) alloy had less durability than those of larger diameter.

At an applied voltage of constant value (constant for tests on an individual igniter but varied between 0.8 and 1.2 volts for tests on different igniters) the strands temperature of platinum as well as platinum-rhodium (90 : 10) wires increased with use. The rate of temperature increase accelerated as the temperature became higher and after reaching a temperature of approximately 1200° C. (as measured with a disappearing filament optical pyrometer without corrections for emissivity) the temperature rise became very rapid until the melting point of the metal was reached and wire failure ensued. New wires of platinum and of platinum-rhodium alloy were found to be catalytically inactive and appear to effect gas ignition by thermal processes only. After several ignitions, however, the wires became increasingly active catalytically and the ignition processes became perceptibly faster. Maximum and constant catalytic activity was obtained after about fifty gas ignitions.

The three most important fundamental factors in gas ignition appear to be (a) temperature of the wire, (b) time during which the gas-air mixture is heated, and (c) the volume of gas-air mixture heated. These factors appear to be inter-dependent, that is, a reduction of wire temperature necessitated heating of a greater volume of gas for a longer period of time to effect igni-

tion. Conversely, to effect ignition in a shorter period of time either higher wire temperature must be used or more gas must be heated or both.

I discovered that the factors enumerated above could be incorporated readily and ideally into an igniter made up of a multiplicity of noble metal wire strands. Wires of platinum and platinum-rhodium (90 : 10) were tested in groups of 6 to 10 strands per igniter, with wire lengths of from 0.25 to 1.25 inches, and with wire sizes Nos. 36, 38 and 40. Manufactured gas, mixed gas, methane (96%) and natural gas were tested and lives of from 300,000 to 800,000 gas ignitions were attained with such igniters.

These tests showed that multiple strand igniters have the following advantages over single strand igniters: (a) Rapid preheating and thus very short ignition time. In tests made the wire strands generally attained ignition temperature before the gas-air mixture reached the hot wires, thus ignition time became a function of length of flash tubes. (b) The durability of multistrand igniters can be extended by utilizing a plurality of strands having different dimensions, so chosen that the several strands in a single igniter operate at different temperatures. Strand materials, lengths and cross-sectional areas can be so chosen that new igniters have only one, two or three strands which attain temperatures high enough to ignite gas. Then, during the course of usage all strand temperatures increase, the hot-test strand failing first. Before failure of the hot-test strand the next hottest attains ignition temperature and becomes functional. However, after the hottest strand fails, the adjacent or next hot-test strands operate at lower temperatures as they no longer receive radiant heat from the strand that failed. This process continues until all strands fail and the overall result is longer igniter life. (c) The wattage necessary to produce gas ignition is less with multiple strand igniters than with single strand igniters.

Multi-strand igniters comprising strands of platinum show little variation in durability for the three sizes tested, namely Nos. 36, 38 and 40. Igniters composed of platinum-rhodium (90:10) wire strands show much greater durability for No. 36 wire strands than for No. 40 wire strands. Strands of No. 40 platinum wire have a greater durability than strands of No. 40 platinum-rhodium, while strands of No. 36 platinum wire have less durability than strands of No. 36 platinum-rhodium.

Stranded wire igniters may be used in place of a pilot light to produce burner ignition through a flash tube or they may be used in an enclosed housing to ignite a gas pilot, which in turn may be used, for example, to ignite an oven burner directly or to light such burner through a flash tube. In either application their performance is rapid, and their durability is very satisfactory.

The above and other objects and advantages of my improved igniter are set forth with particularity in the claims. The invention will be better understood by reference to the following description taken in connection with the accompanying drawing forming a part of this specification, and of which:

Fig. 1 is a partial top plan of a gas range incorporating my invention;

Fig. 2 is a top plan partly in section of my improved igniter;

Fig. 3 is a vertical section of the igniter shown in Fig. 2;

Fig. 4 is a vertical section of a modification of the igniter shown in Figs. 2 and 3; and

Fig. 5 is a vertical section of an oven burner igniter, taken substantially on line 5—5 of Fig. 1.

Referring to Fig. 1 of the drawing, 10 designates generally the cooking top of a conventional gas range provided with four top burners 12. Each of the top burners is provided with a gas supply or mixing tube 14 and with a gas valve, the operating handle of which is designated by numeral 16. An igniter 18, provided with radial flash tubes 20, is located centrally of the top burner. The structure just described is conventional and is merely an illustration of one adaptation of my improved igniter.

Referring now to Figs. 2, 3 and 5 of the drawing, my improved igniter, designated generally by reference character 21, includes a plurality of strands 22 of noble metal as, for example, platinum or platinum-rhodium alloy wire, soldered, as by high temperature silver solder, to a pair of electrically conductive posts 24 and 25, which in turn are supported in a block of insulating material 26. The igniter is supported in the igniter housing 18 in any suitable manner. Low voltage electric current is supplied to the posts by conductors 28 and 29 which are connected to a suitable source (not shown).

I have found in practice that an ideal igniter for use with a domestic gas range, or the like, may be constructed of some 6 to 10 strands of platinum or platinum-rhodium (90:10) wire, with wire sizes Nos. 36, 38 or 40 and with wire lengths of from 0.5 to 1.25 inches. Where it is desirable that the size or cross-sectional area of the wires in a single igniter be uniform and wherein the lengths of the wires vary, the longer wires are placed at the outside of the igniter and the length of the wires is decreased from each side toward the center of the igniter. Where it is desired that the length of the wires in a single igniter be uniform and the cross-sectional area varied, the wires offering the greatest resistance to current flow, that is the smaller diameter wires, are placed on the outside of the igniter, and those offering less resistance to current flow are graduated from each side toward the center of the igniter. It is to be understood, however, that the number, size and length of the wires may be varied to fit the particular use for which the igniter is designed.

The modification of my igniter illustrated in Fig. 4 of the drawing is substantially identical with the igniter illustrated in Figs. 2 and 3, except that in the modified form the wire strands 22' project downward from the supporting posts 24' and 25'. In certain installations this modified igniter has advantages over the igniter illustrated in Figs. 2 and 3 in that by having the wires suspended from the supporting posts the force of gravity tends to keep the wires in properly spaced relation and should one or more of the wires fail they are not apt to interfere with the operation of the other wires.

In the operation of the igniters illustrated in Figs. 2, 3 and 4, when it is desired to light one of the top burners the gas valve of the particular burner is opened and a combustible air-gas mixture is supplied to the burner. Part of the air-gas mixture supplied to the burner flows from a jet (not shown) in the end thereof into the flash tube located adjacent that particular burner, and from the flash tube the air-gas mixture flows into the igniter housing. Simultaneously with the opening of the gas valve the elec-

tric circuit to the igniter is closed, as by a switch as shown in Fig. 5 to be described in detail hereafter. The closing of the switch causes a feeble electric current to flow through the several wires of the igniter in parallel. The current warms the wires appreciably and together with the catalytic effect of the air-gas mixture which passes over the platinum wires, the wires are heated to a temperature which ignites the gas flowing through the flash tube and the flame is flashed back through the tube and ignites the gas at the top burner. As stated above, the several wires of a particular igniter are of different dimensions, therefore, since substantially the same voltage is imposed upon the several wires in parallel, the wire offering the least resistance will be the first to reach ignition temperature, then those offering greater resistance and so on. By this arrangement only one, two or three of the wires, depending upon the age of the igniter, are actually used to ignite the gas, the remaining wires being held in reserve until such time as one or more of the hottest wires fail.

In Fig. 5 of the drawing my improved igniter is shown associated with a pilot burner particularly adapted for igniting an oven burner where-in the igniter per se is identical with the igniter 21 illustrated in Figs. 2 and 3. In this adaptation of my invention an igniter housing 22" provided with an open end, is located immediately adjacent an oven burner (not shown). An air-gas mixture is fed into the igniter housing through a port 30 located in the end of a gas tube 32. This tube is constructed of two lengths of pipe 32a and 32b joined by a sleeve 34 and provided with a baffle 36 having an orifice 38 located therein. Pipe 32a is provided with openings 40, only one of which is shown, which openings are located beyond the orifice 38. A gas valve 42, supplied by a manifold 44, is attached to the opposite end of pipe 32b. This valve may be a multi-ported valve which supplies gas to the oven burner as well as to the igniter. However, the valve illustrated is provided with a single port 46 in the valve plug which supplies gas only to the igniter. The valve plug is provided with the usual stop pin 48 which operates in a slot 50 in the valve casing thus limiting movement of the valve plug to a position bringing the port 46 into register with a port 52 in the valve casing and into a position closing said ports. A key 54 adapted to be inserted into a socket 56 in the end of the valve plug is provided for operating the valve. The key is provided with a shaft 53 which is slidably and rotatably mounted in a housing 60 formed on a flange 62 that extends across the front of the range directly beneath the cooking top. The shaft 58 fits into a sleeve 64 formed on an operating handle 66. A coil spring 68 surrounds the sleeve 64 and tends to urge the key 54 to the inoperative position shown in Fig. 5.

A switch is provided for closing the circuit to the igniter wires 22. This switch includes a pair of spring fingers 70 mounted on the valve housing, but insulated therefrom by insulators 72, and a bridge plate 74 mounted on the key 54, but insulated therefrom by an insulator 76. When the key is forced inwardly to operative position the bridge plate 74 contacts the spring finger 70 to close the circuit. This switch is located in the electric circuit between the source of current (not shown) and the posts 24 and 25 of the igniter.

In operation when it is desired to light the oven burner the operating handle is pushed in-

wardly carrying the key 54 into the socket 56 and carrying the switch bridge into contact with the switch fingers, then the handle is rotated to bring valve port 46 into register with the port 52 whereby gas is supplied to the tube 32. The jet of gas passing through the orifice 38 causes air to be drawn through the openings 40 into the tube which air mixes with the gas and the air-gas mixture passes through the port 30 and above the platinum wires 22 of the igniter. As described above the low voltage current passing through the platinum wires heats these wires and this heating together with the catalytic effect of the air-gas mixture causes the wires of least resistance to quickly reach a temperature which ignites the air-gas mixture flowing through the port 30. The pilot flame formed by the air-gas mixture flowing through this port ignites the oven burner. Once the oven burner is ignited the pilot flame may be extinguished if desired, although it is generally desirable to continue the pilot flame so long as gas is supplied to the oven burner. This is particularly true when the oven burner is operating on low flame. Once the pilot is ignited, however, the operating handle is released whereby the electric circuit to the igniter is opened. The location of the port 30 relative to the wires 22 of the igniter serves several useful purposes, some of which are: the relatively cold gas flowing through the port just prior to ignition does not impinge directly upon the ignition wires and cool them; on the other hand, once the pilot flame is ignited at the port 30, the flame does not heat the wires appreciably, but on the contrary, causes air to be drawn in at the bottom of the open end of the housing 22" which air tends to cool the wires.

Having thus described my invention, I claim:

1. An electro-catalytic igniter for fuel burners comprising a heating and igniting element made of a plurality of strands of wire, means supporting said strands for parallel flow of an electric current therethrough, said strands having different dimensions and being composed of catalytically active material, the construction and arrangement being such that when the same voltage is imposed upon said strands in parallel certain of said strands are heated to higher temperatures than other of said strands, whereby said other strands have a greater life expectancy than said certain strands.

2. An electro-catalytic igniter for fuel burners comprising a heating and igniting element made of a plurality of strands of wire, means supporting said strands for parallel flow of an electric current therethrough, said strands being of different lengths but of the same cross-sectional area and being composed of catalytically active material, the construction and arrangement being such that when the same voltage is imposed upon said strands in parallel certain of said strands are heated to higher temperatures than other of said strands, whereby said other strands have a greater life expectancy than said certain strands.

3. An electro-catalytic igniter for fuel burners comprising a heating and igniting element made of a plurality of strands of wire, means supporting said strands for parallel flow of an electric current therethrough, said strands being of the same length but of different cross-sectional areas and being composed of catalytically active material, the construction and arrangement being such that when the same voltage is imposed upon said strands in parallel certain of said strands

7
are heated to higher temperatures than other of said strands, whereby said other strands have a greater life expectancy than said certain strands.

4. An electro-catalytic igniter for fuel burners comprising a heating and igniting element made of a plurality of strands of wire, means supporting said strands for parallel flow of an electric current therethrough, said strands being of different lengths but of the same diameter and being composed of platinum, the construction and arrangement being such that when the same voltage is imposed upon said strands in parallel certain of said strands are heated to higher temperatures than other of said strands, whereby said other strands have a greater life expectancy than said certain strands.

5. An electro-catalytic igniter for fuel burners comprising a heating and igniting element made of a plurality of arcuate strands of platinum wire, means supporting said strands for parallel flow of an electric current therethrough, said strands being of substantially the same diameter and of different lengths which project upward and outward from said supporting means, the construction and arrangement being such that when the same voltage is imposed upon said strands in parallel the shorter strands are heated to higher temperatures than the longer strands, whereby the longer strands have a greater life expectancy than the shorter strands.

6. An electro-catalytic igniter for fuel burners comprising a heating and igniting element made of a plurality of arcuate strands of platinum wire, means supporting said strands for parallel flow of an electric current therethrough, said strands being of substantially the same diameter and of different lengths which project downward and outward from said supporting means, the construction and arrangement being such that when the same voltage is imposed upon said strands in parallel the shorter strands are heated to higher temperatures than the longer strands, whereby the longer strands have a greater life expectancy than the shorter strands.

7. An electro-catalytic igniter for fuel burners comprising a heating and igniting element made of a plurality of strands of wire of catalytically active material, said strands being of different lengths but of substantially the same cross-sectional area, means supporting said strands for parallel flow of electric current therethrough, means for imposing the same voltage upon said strands, means for conveying fuel gas to said

strands to be ignited thereby, the construction and arrangement being such that when the same voltage is imposed upon said strands in parallel and fuel gas is conveyed thereto certain of said strands are heated to a temperature sufficiently high to ignite the fuel gas while other of said strands stand substantially dormant, whereas after repeated cycles of operation said other strands become effective to ignite gas that is conveyed thereto.

8. An electro-catalytic igniter for fuel burners comprising a heating and igniting element made of a plurality of arcuate strands of platinum wire, said strands being of different lengths but of substantially the same diameter, a pair of electrically conductive posts supporting said strands for parallel flow of electric current therethrough, means for imposing the same voltage upon said strands in parallel, means for conveying fuel gas to said strands to be ignited thereby, the construction and arrangement being such that when the same voltage is imposed upon said strands in parallel and fuel gas is conveyed thereto the shorter of said strands are heated to a temperature sufficiently high to ignite the fuel gas while the longer of said strands stand substantially dormant, whereas after repeated cycles of operation the longer strands become effective to ignite gas that is conveyed thereto.
